UNITED STATES PATENT OFFICE.

NELSON E. KENNEDY, OF NEWARK, NEW JERSEY, ASSIGNOR TO
MAULBETSCH & WHITTEMORE, OF SAME PLACE.

DESIGN FOR A BOW-HOLDING SPRING FOR VIOLIN-CASES.

SPECIFICATION forming part of Design No. 34,477, dated May 7, 1901.

Application filed January 25, 1901. Serial No. 44,768. Term of patent 7 years.

To all whom it may concern:

Be it known that I, NELSON E. KENNEDY, a citizen of the United States, residing at Newark, in the county of Essex and State of New Jersey, have invented and produced a new and original Design for a Bow-Holder for Violin-Cases; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a section of the bow-holding spring, taken at line *x* of Fig. 2; and Fig. 2 is a plan of said spring.

As shown in the drawings, the leading or material feature of the newly-designed bow-holding spring consists of a spring having the configuration outlined in the drawings, in which the flat or strap-shaped and bent piece is shaped to present to view a base *a*, from

which said spring inclines upwardly, as at *b*, to a point above the horizontal plane of the axis of the ring-like end hereinafter referred to. It then extends horizontally, or approximately so, as at *c*, and near its free end it is inclined downward at an inclination opposite the inclination *b*, as at *d*. It is then, in order, curled upward, as at *f*, and then downward, as at *g*, a ring-shaped extremity being at the free end, where the finger may enter and raise the spring to permit the insertion of the bow.

35

What I claim as new is—

The design for a bow-holding spring for violin-cases, substantially as herein shown and described.

In testimony that I claim the foregoing I have hereunto set my hand this 19th day of December, 1900.

NELSON E. KENNEDY.
